(57) **CLAIM**

The ornamental design for a vest for an infant, as shown and
described.

DESCRIPTION

FIG. 1 illustrates a view of the front, top, and right side of my
vest for an infant, showing my design;

FIG. 2 is a view of the rear and top thereof;

FIG. 3 is a top view thereof;

FIG. 4 is a front elevational view thereof;

FIG. 5 is a left side elevational view thereof;

FIG. 6 is a rear elevational view thereof;

FIG. 7 is an elevational view of the front thereof in an
unhooked state; and,

FIG. 8 is an upside down elevational view of the rear thereof
in an unhooked state.
